SUCTION NOZZLE

George Horace Cranmer, Philadelphia, Pa., assignor, by mesne assignments, to Electrolux Corporation, Dover, Del., a corporation of Delaware

Application July 12, 1935, Serial No. 31,026

16 Claims. (Cl. 15—157)

My invention relates to vacuum cleaners and particularly to suction cleaning nozzles for use in connection therewith.

For cleaning under different conditions it is preferable to have different types of cleaning nozzles. For instance, if a rug is being cleaned which has a deep pile in which dirt is embedded, the best results are obtained if the lips of the suction nozzle produce as perfect a seal as is possible with the rug. This causes substantially all of the air to be drawn through the rug, thus dislodging and removing the dirt embedded therein. On the other hand, if the dirt is located on the surface, a better cleaning action is obtained if the air is caused to pass with considerable velocity substantially parallel to the surface in entering the nozzle. Likewise, threads and other comparatively large particles of dirt or foreign matter adhering to the surface of a rug may be more readily removed with a nozzle which causes air-flow in this manner, than with a nozzle which draws the air through the rug.

One of the objects of my invention is to provide a single nozzle which may be used either to draw air through the material of the rug or other surface being cleaned or to cause the air to pass at relatively high velocity parallel to the surface.

Another object of my invention is the provision of such a nozzle which may be quickly and easily altered from one form to another.

A still further object of my invention is to provide a convertible nozzle having selective work engaging portions, one of which may serve to cover the other or may be retracted wholly or partially to within the wall of the nozzle, to uncover the other portion. When so retracted, the portion is substantially out of sight and in no manner interferes with or affects the operation of the nozzle. In accordance with my invention, one of the work engaging portions may be smooth, to give the sealing effect desirable for removing imbedded dirt, while the other portion may be formed with grooves for directing flow of air parallel to the surface undergoing cleaning in order to remove surface dirt. More specifically, my invention involves forming the grooved portion as a stationary rod upon which is rotatably mounted a tubular member having a smooth outer surface and a part cut away. Thus, the tubular member may cover the grooved surface of the rod so as to present a smooth lip to the surface undergoing cleaning, or it may be rotated so that the cut away part is in alignment with the grooves, which are hence uncovered and presented a grooved lip to the rug or other surface.

Further objects and advantages of my invention will be apparent from the following description when considered in connection with the accompanying drawings on which:

Fig. 1 is a rear view of a nozzle including one embodiment of my invention;

Fig. 2 is a bottom view of the nozzle shown in Fig. 1;

Fig. 3 is a bottom view of a portion of the nozzle as shown in Fig. 2 but with certain parts in different position;

Fig. 4 is a view of one of the parts included in the nozzle shown in Figs. 1 through 3;

Fig. 5 is a view of another part;

Fig. 6 is a cross-sectional view taken on the line 6—6 of Fig. 2;

Fig. 7 is a cross-sectional view taken on the line 7—7 of Fig. 2;

Fig. 8 is a cross-sectional view taken on the line 8—8 of Fig. 2;

Fig. 9 is a cross-sectional view taken on the line 9—9 of Fig. 2;

Fig. 10 is a cross-sectional view taken on the line 10—10 of Fig. 8;

Fig. 11 is a perspective view of another of the parts;

Fig. 12 is a cross-sectional view similar to that shown in Fig. 7, but with certain parts in a different position;

Fig. 13 is a bottom view, similar to Fig. 2, but showing a second embodiment of my invention;

Fig. 14 is a cross-sectional view, on an enlarged scale, taken on the line 14—14 of Fig. 13;

Fig. 15 is a cross-sectional view, on an enlarged scale, taken on the line 15—15 of Fig. 13;

Fig. 16 is a cross-sectional view taken on the line 16—16 of Fig. 15; and

Fig. 17 is a top view of the nozzle shown in Figs. 13 through 16.

Referring more particularly to Figs. 1 and 2, reference character 10 designates a nozzle mouthpiece which may be cast of metal, phenol condensate or other suitable material and includes walls defining an elongated suction mouth 11 bounded by a forward lip 12, a rear lip 13, and end lips 14 and 15. These lips are formed with faces which are adapted to contact the surface being cleaned. Mouthpiece 10 is provided with a hollow connection member 16 which communicates with the interior of the mouthpiece and is adapted to be connected with a conduit leading to a vacuum cleaner unit. Such conduit may comprise a stiff tubular member connected to member 16, this tubular member in turn being connected to the vacuum cleaner suction unit by 55

means of a flexible hose. The stiff tubular member serves as a handle for manipulating the suction nozzle. As is well known, the vacuum cleaner unit includes a suction producing device and, 5 preferably, a dust separating member for removing dust from the air.

In the embodiment shown, rear lip 13 is formed with a semi-circular groove 17 which extends substantially the entire length of the lip. Rigidly 10 fixed within this groove is a preferably cylindrical rod 18. One end of rod 18 is formed with a portion 19 of reduced diameter which is received within a bore 20 formed in the material of the lip adjacent the end of groove 17. A hole 21 is 15 formed through the other end of rod 18. A bolt 22 is adapted to pass through hole 21 and engage a tapped hole 23 formed in the lip. This securely fastens the rod in the groove.

The lower face of rod 18, which projects beyond groove 17, is formed with a plurality of transverse grooves 24 and, if desired, with a longitudinal groove 25. These grooves divide this face of rod 18 into a plurality of lugs 26 having circular surface contacting faces.

Rod 18 is of somewhat less diameter than the diameter of groove 17 and is fixed concentrically with respect to the groove. Hence an annular space exists between the rod and the groove. Rotatably mounted on rod 18 is a tubular member 27. Throughout the greater part of its length this tubular member is cut away, as is shown at 28 in Fig. 5, so as to be semi-cylindrical. The ends of member 27 are not cut and constitute complete cylinders 29 and 30 surrounding rod 18. 35 The thickness of the material of tubular member 27 is substantially equal to the thickness of the annular space between rod 18 and groove 17, whereby the tubular member may be rotated so that its semi-cylindrical portion lies behind rod 40 18 as is shown in Figs. 2, 7, and 9, thus exposing the grooves 24 and 25 formed in the surface contacting face of rod 18. Due to this construction, air leakage is essentially prevented through this annular space whether the member 27 is in position 45 to cover rod 18 or retracted within the lip.

On the other hand, if it is desired that these grooves be covered so that the rear lip of the nozzle will effect a seal with the surface being cleaned, member 27 is rotated to the position 50 shown in Figs. 3 and 12 and in this position the semi-circular part of member 27 covers the groove in rod 18.

In order to provide means for locking the tubular member in either position, and for readily 55 rotating it from one position to another, a locking member 35 is provided. Member 35 is formed with a cylindrical portion 36 which is rotatably mounted on the part of reduced diameter 19 of rod 18. Cylindrical portion 36 is connected to a 60 straight or flat portion 37 which extends through a slot 38 formed in cylindrical portion 36 of tubular member 27. Consequently, when member 35 is rotated it causes tubular member 27 to rotate therewith. A groove 40 is formed in the material of the lip adjacent to the end 30 of the tubular member and is in alignment with the slot 38 in the tubular member when the latter is in either of its extreme positions. Member 65 35 is axially slidable on part 19 as well as being 70 rotatably mounted thereon. When moved axially to the position shown in Fig. 10, one end of the flat portion 37 of member 35 enters groove 40 and thus locks the member and tubular member 27 against rotation. If it is desired to rotate the 75 tubular member, locking member 35 is moved or

slid upwardly from the position shown in Fig. 10 until it is disengaged from groove 40 whereupon it may be rotated through 180 degrees. If it is then moved downwardly again it engages slot 40 on the other side of the center about which member 35 was rotated and is securely locked in this position. Member 35 is preferably formed with a convenient hand-grasp portion 42 so that it may be easily manipulated.

In order to cover the head of screw 22 and to provide a smooth surface contacting face for lip 13 throughout its entire length, a semi-cylindrical piece of material 43 may be snapped over rod 18 between the end of tubular member 27 and the end of recess 17. This member 43 is preferably 15 made of the same material as is tubular member 27 and the material has sufficient resiliency so that frictional engagement between member 43 and recesses 44 is sufficient to hold it in place. It may be pried out if it is desired to remove screw 22. 20

The operation of the device will be largely apparent from the above description thereof. In cleaning a rug in which dirt has become embedded, it is best to use the nozzle with tubular member 27 covering the grooves of rod 18. That 25 is, tubular member 27 should be in the position shown in Figs. 12 and 3. This gives lip 13 a smooth sealing surface and inasmuch as the other lips are smooth, an effective seal is obtained between the nozzle and the surface. This prevents 30 air from flowing in large quantities under the lips of the nozzle and causes the air to be drawn substantially entirely through the material. As above explained, this air dislodges and removes the embedded dirt.

If it is desired to remove surface dirt, and particularly such objects as threads which tend to adhere to a rug, hand-grasp portion 42 of member 35 is grasped with the hand and moved longitudinally of the nozzle a slight distance so as to 40 disengage part 37 from groove 40. Thereupon, member 35 may be rotated through 180 degrees from the position shown in Fig. 12 to that shown in Fig. 7 and then moved back longitudinally so as to engage groove 40. This causes tubular 45 member 27 to be rotated to and locked in the position shown in Fig. 7, in which the semi-cylindrical part lies between rod 18 and the bottom of groove 17. The grooves of rod 18 are thus exposed and, when the nozzle is passed over the 50 surface to be cleaned, air enters the interior of the nozzle through these grooves. Thus, a strong current of air is caused to pass parallel to the surface, which air is effective in removing surface dirt including threads or the like. Also 55 the irregular surface presented by the lugs 26 on rod 18 tends to dislodge threads and the like so that they may be picked up by the air.

In Figs. 13 through 17, I have shown a second embodiment of my invention, which differs from 60 that above described primarily in the fact that a different rotating and locking device is employed. Reference character 10 designates the mouthpiece having surface contacting lips 12, 13, 14, and 15. Lip 13 is formed with a semi-cylindrical groove 17 within which is fixed rod 18, the lower face of which is formed with a plurality of transverse grooves 24, as described in connection with the first embodiment. One end of the rod, as is shown in Fig. 14, is received within cylindrical bore 50 formed in the mouthpiece in alignment with groove 17. A bolt 51 extends through an opening 52 formed in the nozzle and engages a threaded aperture in rod 18, thus securing the rod in place.

Tubular member 27 is rotatably mounted on rod 18 and extends the entire length of groove 17. The more central portion of tubular member 27 is cut away, as is shown at 28 in the same manner as described in connection with the first embodiment. The mouthpiece is formed with a tubular bore 53 in alignment with groove 17 which receives an extension 54 secured to the end of tubular member 27. Extension 54 may comprise a short section of rod, of the same diameter as rod 18, which is secured to the tubular member by means of a rivet or the like 55. The outer end of extension 54 is formed with a slot 56 within which is pivotally mounted on a pin or rivet 58, a locking member 57. Member 57 preferably comprises a strip of resilient material doubled back on itself, as is shown clearly in Fig. 16, so that the ends of the strip received within slot 56 tend to separate or expand, thus bearing against the sides of the slot so that the member is frictionally retained against rotation around the pivot 58.

The material of the nozzle adjacent to lip 14 is formed with an inclined groove 59 which communicates at its lower end with the outer end of bore 53 and is open at its upper end. Groove 59 extends at right angles to the axis of bore 53. The dimensions of groove 59 are such that locking member 57 may be pivoted thereinto, and when so pivoted, is substantially flush with the outer surface of the nozzle. The free end of locking member 57 is preferably forked, as is shown at 60 in Fig. 17, in order that it may be easily engaged by the finger of the operator when it is desired to pivot member 57 out of groove 59.

The operation of this embodiment, so far as cleaning is concerned, is the same as that previously described. Consequently, all that need be described of its operation relates to the arrangement for rotating the tubular member 27.

With the parts in the position shown in Figs. 13 through 17, the teeth on rod 18 are exposed. If it is desired to obtain a smooth lip surface, the operator engages the forked end 60 of locking member 57 with the end of his finger and pivots it to the position shown in dot and dash lines in Fig. 17. In this position member 57 is in a straight line with tubular member 27 and extension 54, and hence, rotation of member 57 through 180 degrees causes the tubular member to be rotated so that the semi-cylindrical portion thereof covers the grooves on rod 18. Thereafter, locking member 57 may be pivoted back into groove 59. Obviously, when member 57 is received in groove 59, it serves to lock tubular member 27 against rotation.

I have found that better results are obtained by locating rod 18 and tubular member 27 in the rear lip of the nozzle. However, good results may be obtained by locating these members in the forward lip 12 and, if desired, both the forward and rear lips may be provided with similar arrangements.

It will be noted that in the second embodiment the tubular member may be rotated continuously in one direction, if desired. This is of advantage as it affords an easy and convenient means for dislodging any dirt that might tend to collect in the space between rod 18 and groove 17. To remove such dirt, it is only necessary to rotate the tubular member several revolutions. This serves to work the dirt out from behind the rod.

While I have shown and described two preferred embodiments of my invention, it is to be understood that this has been done for purposes of illustration only and that my invention is not

to be limited thereby, but the scope is to be determined by the appended claims considered in the light of the prior art.

What I claim is:

1. A suction nozzle having selective work engaging portions, one of which covers the other in one position and is retractable at least partially within the wall of the structure defining the nozzle to uncover the other portion. 5

2. A nozzle as defined in claim 1 in which one of the selective work engaging portions is smooth and the other is comb-like. 10

3. A nozzle as defined in claim 1 in which the parts are so constructed and arranged that the cross-sectional area of the mouth of the nozzle 15 is not changed by relative movement of the parts.

4. A nozzle as defined in claim 1 in which one of the work engaging portions is formed by a cylindrical rod and the retractable portion is of cylindrical form rotatable about the cylindrical rod. 20

5. A suction nozzle having a mouth defined by lip structure including selective work engaging portions, one of which is stationary and the other of which is movable, the movable portion having a working position overlying said stationary portion and presenting a different character surface to the work, said movable portion being retractable within the lip structure to expose the stationary portion. 25

6. A nozzle as defined in claim 5 in which there is a space between the stationary and movable portions, which space is closed to substantially prevent air leakage therethrough in any selective position. 30

7. A suction nozzle having selective work engaging portions, one of which is stationary and the other of which is movable, the movable portion covering the stationary portion in one position and being retractable within the lip structure to uncover the stationary portion. 35

8. A suction nozzle including a hollow member having an elongated suction opening bounded by lips having surface contacting faces, one of said lips being formed with a longitudinally extending recess, a fixed member secured in said recess and having a surface contacting face disposed outside said recess and formed with transverse grooves, a member having a smooth surface contacting face, and means for rotatably mounting the last-mentioned member so that it is rotatable about said fixed member to selectively cover and uncover said grooves. 40

9. A suction nozzle including a hollow member having an elongated suction opening bounded by lips having surface contacting faces, one of said lips being formed with a longitudinally extending semi-cylindrical recess, a cylindrical rod of less diameter than said recess fixed in said recess and concentric therewith, said rod having a surface contacting face formed with a plurality of transverse grooves, and a tubular member mounted to rotate about said rod, said tubular member having a semi-cylindrical portion adapted to be rotated so as to cover said grooves and alternatively to be disposed between said rod 65 and the wall of said recess whereby said grooves are exposed. 60

10. A suction nozzle including a hollow member having an elongated suction opening bounded by lips having surface contacting faces, one of said lips being formed with a longitudinally extending semi-cylindrical recess, a cylindrical rod of less diameter than said recess fixed in said recess and concentric therewith, said rod having a surface contacting face formed with 70

- 5 a plurality of transverse grooves, a tubular member mounted to rotate about said rod, said tubular member having a semi-circular portion adapted to be rotated to a position so as to cover said grooves and alternatively to be positioned between said rod and the wall of said recess whereby said grooves are exposed, and means for securing said tubular member in either of said positions.
- 10 11. A suction nozzle including a hollow member having an elongated suction opening bounded by lips having surface contacting faces, one of said lips including a fixed cylindrical bar formed with a plurality of transverse grooves in the surface contacting face thereof, and a tubular member mounted to rotate about said bar, said tubular member having a semi-cylindrical portion adapted to be rotated to selectively cover and uncover said grooves.
- 15 12. A suction nozzle including a hollow member having an elongated suction opening bounded by lips having surface contacting faces, one of said lips being formed with a longitudinally extending semi-cylindrical recess, a cylindrical rod of less diameter than said recess fixed in said recess and concentric therewith, said rod having a surface contacting face formed with a plurality of transverse grooves, and a tubular member rotatably mounted in the annular space between said rod and the wall of said recess, said tubular member having a semi-cylindrical portion adapted to be rotated so as to selectively cover and uncover said grooves.
- 20 13. A suction nozzle including a hollow member having an elongated suction opening bounded by lips having surface contacting faces, one of said lips being formed with a longitudinally extending semi-cylindrical recess, a cylindrical rod of less diameter than said recess fixed in said recess and concentric therewith, said rod having a surface contacting face formed with a plurality of transverse grooves, a tubular member mounted to rotate about said rod, said tubular member having a semi-cylindrical portion adapted to be rotated so as to selectively cover and uncover said grooves, said rod having a portion of reduced diameter adjacent to one end thereof, and a locking member slidably and rotatably mounted on said portion of reduced diameter and extending through a slot in the surrounding portion of said tubular member, said lip adjacent to the end of said tubular member being formed with a slot adapted to receive said locking member to hold the latter against rotation.
- 25 14. A suction nozzle including a hollow member having an elongated suction opening bounded by lips having surface contacting faces, one of said lips being formed with a longitudinally extending semi-cylindrical recess, a cylindrical rod of less diameter than said recess fixed in said recess and concentric therewith, said rod having a surface contacting face formed with a plurality of transverse grooves, a tubular member mounted to rotate about said rod, said tubular member having a semi-cylindrical portion adapted to be rotated so as to selectively cover and uncover said grooves, a surface contacting face formed with a plurality of transverse grooves, and a tubular member mounted to rotate about said rod, said tubular member having a semi-cylindrical portion adapted to be rotated so as to cover said grooves and alternatively to be disposed between said rod and the wall of said recess whereby said grooves are exposed, the thickness of said tubular member being substantially the same as the thickness of the annular space between said rod and said recess.
- 30 15. A suction nozzle including a hollow member having an elongated suction opening bounded by lips having surface contacting faces, one of said lips being formed with a longitudinally extending semi-cylindrical recess, a cylindrical rod of less diameter than said recess fixed in said recess and concentric therewith, said rod having a surface contacting face formed with a plurality of transverse grooves, a tubular member mounted to rotate about said rod, said tubular member having a semi-cylindrical portion adapted to be rotated so as to selectively cover and uncover said grooves, said hollow member being formed with an opening in alignment with said recess and extending from one end of said recess to the outside of said hollow member, an extension of said tubular member rotatably received in said opening, and a locking member pivotally connected to said extension, said hollow member being formed with a groove extending at right angles to said opening and adapted to receive said locking member when the latter is pivoted to locking position.
- 35 16. A suction nozzle including a hollow member having an elongated suction opening bounded by lips having surface contacting faces, one of said lips being formed with a longitudinally extending semi-cylindrical recess, a cylindrical rod of less diameter than said recess fixed in said recess and concentric therewith, said rod having a surface contacting face formed with a plurality of transverse grooves, a tubular member mounted to rotate about said rod, said tubular member having a semi-cylindrical portion adapted to be rotated so as to selectively cover and uncover said grooves, said hollow member being formed with openings in alignment with said recess and extending from either end of said recess to the outside of said hollow member, said rod being secured to said hollow member within one of said openings, an extension of said tubular member rotatably received in the other of said openings, and a locking member pivotally connected to said extension, said hollow member being formed with a groove extending at right angles to the last-mentioned opening and adapted to receive said locking member when the latter is pivoted to locking position.
- 40 45 50 55 60

GEORGE HORACE CRANMER.
